UNITED STATES PATENT OFFICE.

DANA H. BENJAMIN, OF CLEVELAND, OHIO, ASSIGNOR TO THE GUGGENHEIM LAUNDRY MACHINERY COMPANY, OF CLEVELAND, OHIO, A CORPORATION OF OHIO.

CLOTHES-PRESSING MACHINE.

1,218,609.

Specification of Letters Patent.

Patented Mar. 6, 1917.

Application filed March 8, 1915. Serial No. 12,954.

To all whom it may concern:

Be it known that I, DANA H. BENJAMIN, a citizen of the United States, residing at Cleveland, in the county of Cuyahoga and State of Ohio, have invented certain new and useful Improvements in Clothes-Pressing Machines, of which the following is a specification.

This invention relates to improvements in clothes pressing machines and particularly to that class of such devices wherein the garments are subjected to pressure between heated members.

More specifically the invention relates to a clothes pressing machine comprising a frame, a lower buck supplied with steam from any suitable source, an upper buck or platen also supplied with steam, both of said bucks being yieldingly mounted, and an intermediate movable buck adapted to operate between the ironing faces of the other bucks, the arrangement being such that while one garment is being pressed between the intermediate buck and the lower stationary buck, another may be placed upon the top of the former for engagement with the upper buck, when the intermediate buck is released from the lower buck.

The invention may be further briefly summarized as consisting in the construction and combination of parts hereinafter set forth in the following description, drawings and claims.

Referring to the drawings, Figure 1 is a front elevation; Fig. 2 is a section through the several bucks; Fig. 3 is a left end elevation; Fig. 4 is a detail showing the yielding means for the upper buck; Fig. 5 is a sectional view of this device; Fig. 6 is a top plan view of the machine; Fig. 7 is a detail view of the equalizer for the upper buck; Fig. 8 is an end view of the driving mechanism; Fig. 9 is a vertical longitudinal section of this driving mechanism; Fig. 10 is a top plan of the same; Fig. 11 is a detail section of the pin structure; and Fig. 12 is an end view of the clutch member.

In carrying out the invention any preferred form and construction of parts may be employed so long as it possesses the necessary characteristics, but I have shown one form in the drawings, which is effective, and in such embodiment 1 represents a base provided with a stationary buck standard 1' having an upper platform portion 2 pro-

vided with openings adapted to receive bolts 3, one arranged near each corner and all secured rigidly within a buck support 4. These bolts receive between the platform 2 and the base of the support 4 suitable springs 5. Below the platform 2 these bolts are provided with nuts 6. The support 4 is cut in from one end to form a recess 7 for receiving the portion of the garment which passes under this buck. Secured to the top of this support 4 is a lower ironing buck 8 preferably provided with a steam chamber 9 to be furnished with steam from any suitable source.

To the rear of the standard 1 is a main operating shaft standard 10 and an auxiliary standard 11. These two standards are provided with bearings 12 and 13 respectively. These bearings support a rock shaft 14 extending beyond both bearings, the portion 70 extending beyond the bearing 12 being tapered at 15 and reduced and threaded at 16 for a purpose to be described. Mounted upon the rock shaft 14 are intermediate buck supporting brackets 17 and 18; the former being rigidly secured to the shaft just inside of the bearing 12, and the latter being rigidly secured to the shaft just outside of the bearing 13. These two brackets are integral with an intermediate buck 19 provided with a steam chamber 20 to be supplied with steam from any suitable source, and in any suitable manner. Loosely mounted upon the rock shaft 14 is an upper buck supporting bracket comprising side portions 21 spaced apart and each having at its outer end a shaft receiving portion 22, these two bearing portions receiving a shaft 23 which passes through eyes 24 preferably formed integral with the upper buck 25. This upper buck has a steam chamber 26 therein. The shaft 23 is held within the shaft receiving portions 22 by means of suitable set screws 27 holding the shaft against rotation. Secured to this shaft between the inner eyes 24 85 is an equalizing member 28 having laterally extending portions 29 provided with springs 30 engaging the upper face of the upper buck on either side of the central longitudinal axis thereof and serving to give 90 it a definite relationship with respect to the intermediate buck member.

The side portions 21 of the upper buck supporting bracket merge into one on the side of the shaft opposed to the upper buck 110

and form a boss 31 which is slotted at 32 and receives a bolt 33. This bolt is provided with a head 34 engaging in a recess 35 formed in a block 36 provided with a flange 37 secured by bolts 38 to the upper end of a standard 39. The shank of the bolt passes through an opening 40 in the block 36. The block 36 below the head of the bolt 34 is recessed at 41 to receive a tongue 42 of a bar 43 which extends to the front of the machine and is there provided with a hand piece 44. The use of the tongue 42 and the bar 43 to which it is connected will be described later. Above the block 36 the shank 10 of the bolt is provided with a nut 45 engaging a spring 46. This spring thrusts against a washer 47 engaging the underside of the boss 31 while on the upper side of the boss the shank is provided with a nut 48 held in place by a check nut 49.

In order to transmit pressure from the driving mechanism to the bucks the tapered portion 15 of the shaft 14 is provided with a hub 50 having a downwardly extending arm 25 51. This arm has at its lower end a fork 52 provided with a cam 53 on the outside of the end of each fork. The hub 50 is provided with a laterally extending arm 54 having a counterweight 55 secured thereto. A suitable nut 56 holds the hub 50 in place, and the hub is fastened in any suitable manner to the tapered portion so that these parts 30 operate the shaft.

Coöperating with the cam 53 is suitable 35 driving mechanism, and it comprises a bearing bracket 57 provided with a bearing portion 58 having a cap 59. This bearing receives a shaft 60 to which is keyed a peripheral cam 61 in extent a little greater than a 40 semi-circle.

Assuming that the parts are in the position shown in Fig. 3, the operator moves the intermediate member upward until it is in engagement with the upper buck, then 45 places the garment upon the lower buck. He then shifts the intermediate buck until it engages upon the top of the garment and applies power through mechanism to be described, causing the cam 61 to rotate in a 50 counter-clockwise direction, as shown in Fig. 3, and move the arm 51 and the intermediate buck in a clockwise direction. This causes pressure to be brought to bear between the intermediate buck and the lower buck. The power mechanism is then released from the shaft 60.

The power transmitting mechanism employed for operating the cam 61 comprises a casing 62 secured to the base and adapted 60 to receive the shaft 60, as shown in Fig. 9. This casing is provided with bearings 63 and 64 for supporting the shaft, and an upwardly extending bearing 65 in the bottom of the casing, for a purpose to be described. 65 The casing is also provided with a suitable

worm shaft bearing 66 extending outside of the casing, as shown in Fig. 10. Loosely mounted upon the shaft 60 within the casing 62 and in the bearing 63 is a beveled gear 67 having in the side face thereof clutch pins 68 preferably four in number. Opposed to this beveled gear 67 is a combined bevel and worm gear member 69 having a gear portion 70 corresponding to the beveled gear 67 and a worm gear portion 71 which meshes with a suitable worm 72 mounted on a worm shaft 73 supported in the casing in the bearing 66 and extending out beyond the same where it is driven by any suitable means. In the face of the combined beveled and worm gear member, and within the beveled teeth are suitable clutch pins 74 similar to the pins 68. All of these pins co-operate with sockets 75 in the side faces of a movable clutch member 76 loosely splined upon the shaft 60. This movable clutch member 76 is provided with a groove 77 to be engaged by suitable shifting mechanism to be described. Mounted in the bearing 65 is a trunnion 78 of a planetary beveled gear 79 which meshes with the beveled gears 68 and 70. The shaft 60 extends through the bearing 64 and is there provided with a clutch shifting disk 80 provided with a pair of diametrically disposed shifting pin devices, and each of these devices consists of a supporting boss 81 preferably formed integral with the disk 80 and adapted to receive a pin 82 provided with a shoulder 83 for limiting the movement to the left, as shown in Fig. 11, and a cam engaging head 84. Each pin is preferably provided with an opening 85 adapted to receive a spring 86 engaging a strip 87 held upon studs 88 formed integral with the boss 81, by screws 89. The normal tendency of the pin is toward the left, as shown in Fig. 11. The cam engaging head 84 is engaged by a cam 90 which is secured to a lug 91 preferably cast integral with the casing 62. This cam is cut away at each end, as shown at 92 in Figs. 10 and 11, so as to permit the narrow portion of this cam to engage behind the cam engaging head 84. It will be seen from this construction that as the disk 80 rotates and one of the pins is brought to the proper position, its head will engage the cut-away portion 92 and cause the pin to be withdrawn from the disk, for a purpose which will later appear.

In order to shift the clutch member 76, suitable mechanism is provided and it comprises a sliding bar 93 supported in suitable brackets 94 on top of the casing, as shown in Fig. 9, and this bar has secured to it a clutch shifting arm 95 extending through a suitable opening 96 in the casing and engaging in the groove 77. This bar 93 extends beyond the disk 80, as shown in Figs. 9 and 10, and is there provided with a lug

97 adapted to engage in a cam groove 98 formed in the periphery of an arc-shaped member 99. This arc-shaped member is integral with a lever 100 which is keyed by 5 means of a key 101 to a rock shaft 102 provided at its inner end with a beveled gear 103 meshing with a beveled gear 104 secured to a treadle shaft 105 having a double arm treadle 106 extending out at the front 10 of the machine. The arc-shaped member 99 is provided upon its inner face with a lug 107, shown in section in Fig. 9 and in dotted lines in Figs. 8 and 10, and this lug is adapted, at the proper time, to be engaged 15 by one of the pins 82.

The groove 98 in the arc-shaped member is preferably spiral in its arrangement, as shown in Fig. 10, except for a portion at the center which is straight, and the arrangement 20 of these parts is such that when the lever 100 is shifted in a clockwise direction, as shown in Fig. 8, the bar 93 will be moved to the left, as shown in Fig. 9, the movement of the lever in the opposite direction 25 causing the opposite movement of the bar 93.

The operation of this gearing is as follows: Assuming that the intermediate buck is thrown into engagement with the upper buck, as shown in dotted lines in Fig. 8, and 30 that the power is transmitted to the gears 67 and 70 such that they are driven in opposite directions, then the operator, by means of the treadle, shifts the lever 100 in a direction such that the bar 93 shifts the clutch 35 member 76 into engagement with the proper one of these beveled gears. This causes the shaft 60 to rotate and the cam 61 to engage one of the cam portions 53 and force the bucks into pressing engagement. The movement 40 of the lever 100 is possible by reason of the fact that the pin 82 which is at that time in the position shown in Fig. 10, is withdrawn by reason of the engagement of the cam engaging head 84 with the cam 90. 45 As soon, however, as the cam 60 has made a half turn the other pin 82 engages the lug 107 picking up the lever 100 and causing it to be rotated back to neutral position, which is that shown in Figs. 8 and 10. In doing 50 this, however, the bar 93 is shifted, but the parts are so timed that the clutch engaging portions do not release until the pin, which is moving upward at that time is completely withdrawn. In this way the cam 61 stops 55 in engagement with the cam 53 and holds the bucks together under pressure. The operator then presses the same portion of the treadle, thus causing a similar operation of the driving mechanism and bringing 60 about a release of the intermediate buck.

When very thick fabric is to be pressed it is placed upon the intermediate buck 19 and operated upon by this buck and the upper buck and in order to relieve the tension 65 on the spring 46 due to the thickness of

the fabric the tongue 42 is withdrawn by operating the rod 43 forward a handle 44 at the forward end of the machine being utilized for this purpose.

Having described my invention, I claim:—

1. In a pressing machine, a pair of spaced bucks, a movable buck coöperating with said spaced bucks, and freely movable into engagement with either, and pressure mechanism for forcing the movable buck into pressing engagement with either buck. 7b

2. A pressing machine, a pair of spaced bucks yieldingly mounted, an intermediate buck for coöperation therewith and movable into engagement with either, and means for forcing the intermediate buck into pressing relationship with either of said spaced bucks. 80

3. In a pressing machine, a pair of spaced bucks each having an ironing surface, an intermediate buck having an ironing surface on both of its sides, said surfaces coöperating with the ironing surfaces of the spaced bucks, and pressure mechanism for forcing the intermediate buck into pressing relationship with respect to either of the spaced bucks. 85

4. In a pressing machine, a standard, a lower buck yieldingly mounted thereon and having an ironing surface upon its upper face, an upper buck support yieldingly mounted, an upper buck carried thereby, an intermediate buck coöperating with the upper and lower bucks, means for supporting 100 said intermediate buck whereby it may be shifted from the upper to the lower buck, and means for forcing the intermediate buck into pressing relationship with either the upper or the lower buck. 105

5. In a pressing machine, a standard, a lower buck yieldingly mounted thereon and having an ironing surface upon its upper face, an upper buck support yieldingly mounted, an upper buck carried thereby, an intermediate buck coöperating with the upper and lower bucks, means for supporting 110 said intermediate buck whereby it may be shifted from the upper to the lower buck, means for forcing the intermediate buck 115 into pressing relationship with either the upper or lower buck, and means for permitting the equalization of the upper and lower bucks with respect to the intermediate buck so that there will be a uniform engagement 120 of the ironing faces.

6. In a pressing machine, a frame, a lower buck yieldingly mounted upon said frame, an upper buck supporting member mounted in said frame, an upper buck carried thereby, yielding connections between the upper buck support and the frame, an intermediate buck mounted to swing in an arc between the upper and lower bucks, and means for forcing the intermediate buck 130

into pressing engagement with either the upper or lower buck.

7. In a pressing machine, a frame, a lower buck yieldingly mounted upon said frame, an upper buck supporting member mounted in said frame, an upper buck carried thereby, yielding connections between the upper buck support and the frame, a rock shaft mounted on said frame, an intermediate buck operatively connected to said rock shaft and adapted to swing between the upper and lower bucks, an operating lever for said rock shaft, and means for engaging the same to bring about a pressing relationship between the intermediate buck and either of the upper and lower bucks.

8. In a pressing machine, a frame, a lower buck yieldingly mounted upon said frame, an upper buck supporting member mounted in said frame, an upper buck carried thereby, yielding connections between the upper buck support and the frame, a rock shaft mounted on said frame, an intermediate buck operatively connected to said rock shaft and adapted to swing between the upper and lower bucks, an operating lever for said rock shaft, and means for engaging the same to bring about a pressing engagement between the intermediate buck and either of the upper and lower bucks and comprising a rotatable cam, and a pair of cam shoes carried by said lever and adapted for coöperation with the rotatable cam for bringing about a pressing relation of the intermediate buck with respect to the upper and lower bucks.

9. In a pressing machine, a frame, a lower buck yieldingly mounted upon the frame, a rock shaft mounted on the frame, an upper buck supporting member mounted upon said rock shaft and having arms extending in two directions, an upper buck swiveled to the arm on one side of said shaft, a yielding connection between the frame and the other arm, an intermediate buck operatively connected to the rock shaft, an operating arm for said shaft, and means for engaging said operating arm for bringing about a

pressing engagement of the intermediate buck and either of the upper and lower bucks.

10. In a pressing machine, a frame, a lower buck yieldingly mounted upon the frame, a shaft mounted in the frame, an upper buck operating lever having a pair of buck supporting arms and a holding arm, an upper buck pivotally connected to said buck supporting arms, a yielding connection between the holding arm and the frame and comprising a rod engaging the holding arm, suitable stops carried by said rod above the arm, a spring below the arm, means upon the rod for adjusting the tension of the spring, connections between the rod and the frame and comprising a socket member, a head carried by said rod engaging said socket member, said head having movement in said socket, and means for varying such movement, an intermediate buck, and means for manipulating the same.

11. In a pressing machine, a frame, a lower buck yieldingly mounted upon the frame, a shaft mounted in the frame, an upper buck operating lever having a pair of buck supporting arms and a holding arm, an upper buck pivotally connected to the holding arm, a yielding connection between the holding arm and the frame and comprising a rod engaging the holding arm, a suitable stop carried by said rod above the arm, a spring below the arm, means upon the rod for adjusting the tension of the spring, and connections between the rod and the frame and comprising a socket member, and a head carried by said rod engaging in said socket member, said head having movement in said socket, a slide in the socket member and adapted to engage under the head of said rod, an intermediate buck, and means for manipulating the same.

In testimony whereof I affix my signature in presence of two witnesses as follows:
